US00D797116S

(12) **United States Design Patent** (10) **Patent No.:** **US D797,116 S**
Chapman et al. (45) **Date of Patent:** **** Sep. 12, 2017**

(54) **DISPLAY SCREEN OR PORTION THEREOF
WITH GRAPHICAL USER INTERFACE**

(71) Applicant: **General Electric Company**, Schenectady, NY (US)

(72) Inventors: **Philip E. Chapman**, Oregon, WI (US); **Robert Q. Tham**, Middleton, WI (US); **Michael Foulis**, Madison, WI (US); **Wesley Moreau**, Cottage Grove, WI (US)

(73) Assignee: **General Electric Company**, Schenectady, NY (US)

(**) Term: **15 Years**

(21) Appl. No.: **29/537,768**

(22) Filed: **Aug. 28, 2015**

Related U.S. Application Data

(63) Continuation of application No. 29/428,371, filed on Jul. 30, 2012, now Pat. No. Des. 741,879.
